CLAIM

The ornamental design for a bottle, as shown and described.

DESCRIPTION

FIG. 1 is a top view of a bottle showing the new design; FIG. 2 is a perspective view of a bottle showing the new design;

FIG. 3 is a front view thereof;

FIG. 4 is a right side view thereof, the left side view being a mirror image thereof;

FIG. 5 is a rear view thereof; and,

FIG. 6 is a bottom view thereof.

The dashed lines shown in the drawing views depict portions of the bottle that form no part of the claimed design.

The dot-dash lines in the drawings define the bounds of the claimed design and form no part thereof.
